FORMATION OF FILAMENTS OF ARTIFICIAL SILK AND THE LIKE

Robert de Stoutz, Zurich, Switzerland

Application January 23, 1936, Serial No. 60,400
In Switzerland February 2, 1935

2 Claims. (Cl. 103—162)

In another application for patent of the present applicant Ser. No. 719,506, filed April 7, 1934 and allowed October 30, 1935, for Pumps, on which has issued Patent No. 2,028,964, there is shown and described an apparatus or mechanical device, designed for use in the manufacture of artificial silk, in which filaments are formed by the extrusion of a cellulose composition through a minute orifice from the container in which it is held in a semi-liquid or pasty form, such apparatus comprising a cylinder block within a housing, the cylinder block and the housing being relatively rotatable the one with respect to the other and the cylinder block being formed and provided with a plurality of pump cylinders and pistons parallel with the axis of the cylinder block, a co-operating, stationary working head being formed with channels through one of which the cellulose composition is drawn from the source of supply into each cylinder in turn and from the other of which the composition is forced to and through the orifice of extrusion by the action of each cylinder and piston in turn. Annular cams are provided for co-operation with the pistons whereby in the relative rotation of the cylinder block and housing each piston is caused by the action of what may be called the suction cam, while the corresponding cylinder is in communication with what may be called the suction channel, to perform a suction stroke by which the cylinder is filled with the composition, and whereby, in the further relative movement of the cylinder block and the housing, each piston in turn is caused by the action of what may be called the pressure cam to perform a pressure stroke by which the composition in the corresponding cylinder is forced by the pressure stroke of the piston into the pressure channel and thence to the extrusion orifice. The device or apparatus now to be described and in which the present invention is exemplified embodies the above mentioned elements of the former apparatus, with certain improvements now to be described.

As filaments produced by the extrusion of a cellulose composition must be as nearly uniform as it is possible to make them, it will be appreciated that a very high degree of uniformity in operation must be attained in the apparatus provided, fluctuations of more than one-tenth of 1 per cent in the output not being tolerated. In the development of the present invention it has been realized that uniformity of output depends on the pressure stroke of the pump and not on the suction stroke, which can vary within rather wide limits if not less than the proper amount of the composition is taken into each cylinder at each suction

stroke. It is essential, however, to uniformity in the output that the pressure stroke of each piston shall take place without axial clearance, that is, that each piston shall be actuated positively and constantly by the pressure cam during the entire pressure stroke. Because of wear on the working parts of the piston operating device there would ordinarily be developed some axial clearance which, if not remedied, would entail corresponding delay in the beginning of the pressure stroke of the piston with corresponding irregularity in the output.

In the apparatus shown in the application above mentioned it was sought to take up such axial clearance by the provision of springs whereby the piston heads were pressed constantly against the pressure cam. It has been found, however, that the employment of such springs entails the disadvantage of pressure exerted upon the cooperating members with the result of increased wear. Moreover, as is always the case when springs are employed, the springs, not being positive in action, are not sufficiently reliable.

In accordance with the present invention the difficulties due to the employment of springs interposed at some point between the pressure cam and the pistons are eliminated by the establishment of such operative relation between the pistons, the suction and pressure channels and the suction and pressure cams, that each suction stroke of each piston is longer by a surplus amount than the pressure stroke which determines the pump output, the quantity of composition drawn into each cylinder in the surplus part of the suction stroke being returned into the suction channel of the apparatus before the pressure stroke begins with an initial stroke velocity zero, that is, with a minimum stroke velocity. At this point in the operation the surplus composition in the cylinder, whether the quantity be greater or less, having been returned to the source through the suction channel and a predetermined quantity, measured by the length of the piston pressure stroke remaining in the cylinder, the piston stroke of the piston is effected by the pressure cam, which then acts upon the piston, and the predetermined quantity of composition is delivered through the pressure channel, with which the cylinder is then in communication, to the extrusion orifice. In this manner, as communication is established between the suction channel and each of the cylinders in succession, a quantity of composition, in excess of the capacity of the quantity measured by the pressure stroke of the piston, is returned to the source through the suction chan-

nel and thereafter, as the cylinder is placed in communication with the pressure channel the piston is driven forward by the pressure cam and forces the measured quantity of the composition 5 through the pressure channel to the extrusion orifice. It will be understood, of course, that the cylinders are so positioned in the cylinder block in relation to each other and to the suction and pressure channels that, although the delivery of 10 the composition from each cylinder begins with the initial velocity zero, the action of the successive cylinders and pistons, in supplement one to another, is such that the continuous product of the extrusion orifice is uniform, the volume de- 15 livered from each cylinder being dependent solely upon the pressure stroke of the corresponding piston, and being independent of the suction stroke of the piston. It will be observed that there is at the beginning of the pressure stroke by which 20 the output of the pump is determined no clearance between the piston and the pressure cam and that contact (either direct or indirect) between the pressure cam and the piston continues during the entire pressure stroke under the influence of 25 the friction between the piston and the cylinder and the hydraulic discharge pressure.

In the drawing there is illustrated one convenient and practical embodiment of the invention, in which the cylinder block rotates within the housing and with respect to the working head.

In the drawing—

Figure 1 is a view in longitudinal, axial section of an extrusion device or pump constructed in accordance with the invention.

Figure 2 is a face view of the working head, and Figure 3 is a diagrammatic view illustrating the relations of a cylinder, a piston, pressure and suction cams, and suction and pressure chan- 35 nels.

In the embodiment of the invention illustrated a suitable housing 1 is provided with end members 2 and 3, the latter providing a bearing for the operating shaft 4 and having formed in its plane face 25 arcuate channels 17 and 18, the channel 17, which may be referred to as the suction channel, being in communication with the source of supply of the cellulose composition through the channel 19, 20 and 21 and the channel 18, which may be called the pressure channel, being in communication with the extrusion orifice, not necessary to be shown, through the channel 22, 23.

The shaft 4 has at 15 a non-rigid driving connection with a cylinder block 5 which is thereby rotated within the housing 1. This block is formed 55 with a plurality of cylinders 6 parallel with the axis of the pump.

At the upper or rear end of the pump there is secured to the end member 2 a non-rotating annular pressure cam 8, which acts through interposed sliding bolts, one of which is shown at 9 in Figure 1, against the heads 10 of the pistons 7, one such piston being shown.

It will be understood that as the cylinder block rotates in the housing the bolts 9, bearing against the annular cam 8, and against the piston heads 10, are forced forward or downward and the pistons 7 perform their pressure strokes.

The suction strokes of the pistons are effected 70 in the rotation of the cylinder block by an annular suction cam 11 which, in the construction shown, acts upon slide bars 13, disposed in longitudinal channels 24 formed therefor in the periphery of the cylinder block, each slide bar 13 being formed 75 with a lug or nose 14 which, through an opening

formed therefor in the wall of the corresponding cylinder, engages the head 10 of the corresponding piston 7 to effect its return or suction stroke.

A spring 16, bearing at one end against the driving connection 15 and at the other end through a plate 26 and ball 27 against the cam member 8, serves to secure proper application of the cylinder block against the plane face 25.

In the rotation of the cylinder block the successive cylinders 6 are brought alternately into communication with the suction channel 17 and the pressure channel 18. The fluent composition enters the pump at 19, reaches the suction channel 17 through the channel 20 and 21 and then, on the suction stroke of the piston, is drawn into the cylinders 6 in succession. At the time of the pressure stroke of each piston the composition is forced by the pressure stroke of the piston into the channel 22, 23 and thence to the extrusion orifice.

In order that the relation of the several working parts of the pump may be understood reference may be had to the diagrammatic illustration of such relations in Figure 3 in which successive positions of a piston are indicated at I-VIII, respectively. In this diagrammatic representation the piston 7 is shown as bearing directly against the pressure cam 8 and as provided with a lug or nose 13* for direct cooperation with the suction cam 11, the bolts 9 and the slide bars 13 being omitted from this figure in order to avoid confusion.

It may be assumed that a limited amount of axial play, due to wear, has been developed, as indicated at s. It is also understood that the individual piston under consideration in the cylinder 6 in which it is reciprocated moves from left to right, as shown in Figure 3, and in a complete rotation of the cylinder block assumes, under the influence of the suction and the pressure cams, the successive positions indicated at I-VIII, respectively. In the position I the piston is about to begin at normal level

its normal pressure stroke with an initial velocity zero, the connection of the cylinder with the pressure channel 18 just then beginning. In the continued relative movement of the cylinder block and cams the piston, acted upon by the rising curve of the cam 8, is shown at position II as having completed about half of its pressure

stroke which is completed as the piston passes toward position III where it is represented as having completed its pressure stroke while the connection of the cylinder to the pressure channel 18 is about to be cut off. At position IV the piston is still shown as at the forward limit of the pressure stroke with the connection of the cylinder with the suction channel 17 about to begin.

At position V the piston is shown as beginning its suction stroke, with the cylinder in full communication with the suction channel 17. In the continued movement the piston is withdrawn further than indicated in the position I, the pressure cam having a drop beyond normal level greater than in the position I and the suction cam having a greater lift, whereby the piston has a suction stroke greater than the normal pressure stroke.

If the normal pressure stroke is indicated by the double pointed arrow a then the complete suction stroke is represented by the double pointed arrow a plus b minus s and there is thereby drawn into the cylinder a quantity of the liquid composition greater than the amount driven from the cylinder in the pressure stroke of the piston. In the

position VI the piston is shown as having completed its suction stroke and as having moved forward to the position indicated in the position I, the connection of the cylinder with the suction channel 17 about to begin.

At position VII the piston is shown as beginning its pressure stroke, with the cylinder in full communication with the pressure channel 18. In the continued movement the piston is withdrawn further than indicated in the position VI, the suction cam having a drop beyond normal level greater than in the position VI and the pressure cam having a greater lift, whereby the piston has a pressure stroke greater than the normal suction stroke.

If the normal suction stroke is indicated by the double pointed arrow a then the complete pressure stroke is represented by the double pointed arrow a plus b minus s and there is thereby drawn into the cylinder a quantity of the liquid composition greater than the amount driven from the cylinder in the suction stroke of the piston. In the

position VIII the piston is shown as having completed its pressure stroke and as having moved forward to the position indicated in the position VII, the connection of the cylinder with the pressure channel 18 about to begin.

position VI and also in the position VII the cylinder is shown as in full communication with the suction channel 17. Immediately following the extreme drop of the pressure cam and the extreme lift of the suction cam 11 the pressure cam has a sharp short lift and the suction cam has a corresponding short but sharp drop, whereby the piston is restored in the position VIII to the same normal level as indicated in the position I and the surplus of liquid in the cylinder is returned to the suction channel, the cylinder, as it passes out of communication with the suction channel 17 then retaining the definite, predetermined measured quantity of liquid, in readiness to be discharged into the pressure channel as soon as the piston moves from the position VIII to the initial position I.

As shown in Figure 3 the working faces of the pressure cam 8 and the suction cam 11 are equidistant at all points. If it be assumed that the initial position of the piston and cylinder is that which it has when the surplus composition has been returned to the suction channel, as at the position VIII, and the piston is in readiness for its pressure stroke, it is retained in that position, while the cylinder moves forward from the position VIII, where it passes out of communication with the suction channel 11, to the position I, where it communicates with the pressure channel 18. Both cams therefore have a dwell at what may be called the normal height, from position VIII to position I. Then cam 8 has a lift of the height represented by the double pointed arrow a and the cam 11 has a corresponding drop, the pressure stroke of the piston being thus effected. The lift of cam 8 is succeeded by a dwell while the cylinder passes from communication with the pressure channel 18 to communication with the suction channel 11. This dwell is succeeded by a drop, in the case of the pressure cam, and a lift, in the case of the suction cam, greater than the first lift and drop, represented by the double pointed arrow $a+b$, whereby the piston is caused to take a maximum charge into the cylinder, which is then in communication with the suction channel, as represented at positions VI and VII. The cylinder still being in communication with the suction channel 17, this maximum drop of the cam 8 and maximum lift of the cam 11 are at once succeeded by a slight lift of cam 8, with corresponding drop of cam 11, whereby the piston forces the surplus charge back into the suction channel 17 and is itself restored to the normal level, at the position VIII, in readiness to deliver the measured charge into the pressure channel 18.

It will be seen that the quantity of liquid discharged into the pressure channel by each piston is determined exactly by the pressure stroke of the piston which is unvaried in length and that the surplus quantity and only the surplus quantity which is taken into the cylinder during the suction stroke of the piston, whether it be larger or smaller, is returned to the suction channel. It will be noted that the maximum drop of the pressure cam and the maximum lift of the suction cam are located in such relation to the suction channel that the charge is completed and the surplus is returned to the suction channel while the cylinder is in communication with the suction channel and that the following pressure stroke begins in I with the initial velocity zero.

The axial clearance s developed by wear can

be increased to the value b without affecting the uniformity of the normal pumping operation, which depends only on the pressure stroke of the piston. The relations of normal pressure stroke, suction stroke and surplus suction and pressure stroke are represented in Figure 3 in which the normal pressure stroke, beginning at normal level, is represented by the line a , the suction stroke is represented by the lines $a+b-s$ and the surplus suction and pressure stroke is represented by $b-s$. It will also be understood that the length of dwell is not important, it being evident that it might be zero. Furthermore, in a pump having the sine motion without dwell the normal pressure stroke begins at the dead center with the speed zero, while the feeding of the composition into the pressure channel begins, because of the overlap, somewhat later and not at the zero piston speed.

It will be understood that each of the several pistons operates in the manner already described and that the several cylinders and pistons are so placed that the discharge effected by each piston is combined with the discharge effected by other pistons, so that there is no variation in the product of the pump at the extrusion orifice.

Wear of the pistons and cams within the limit above suggested may take place without affecting the product of the pump and without the use of springs, whereby the pressure of the contacting parts is diminished with corresponding decrease in wear. All piston movements are effected positively and therefore with the greatest reliability.

The design of the pump can be varied without departing from the spirit of the invention. Thus the cylinder block might be stationary while the casing, cams and working face are rotated and the cylinders and pistons might be arranged radially.

I claim as my invention:

1. In an apparatus of the character described, the combination of a working head having a suction channel connected to the source of supply and a pressure channel, a cylinder block having a plurality of cylinders and pistons, the working head and the cylinder block having relative movement the one with respect to the other and each cylinder being arranged for communication alternately with the suction channel and the pressure channel, and suction and pressure cams co-operating with the pistons to effect the working strokes of the pistons, the normal pressure stroke of each piston for delivery to the pressure channel beginning at normal level with a minimum pressure stroke velocity and the suction cam having a maximum lift and the pressure cam maximum drop beyond said normal level while the cylinders are in communication with the suction channel.

2. In an apparatus of the character described, the combination of a working head having a suction channel connected to the source of supply and a pressure channel, a cylinder block having a plurality of cylinders and pistons, the working head and the cylinder block having relative movement the one with respect to the other and each cylinder being arranged for communication alternately with the suction channel and the pressure channel, and suction and pressure cams co-operating with the pistons to effect the working strokes of the pistons, the working faces of the cams being equidistant and having a dwell at normal level, the delivery stroke of each piston to the pressure channel beginning at

normal level with a minimum piston stroke velocity, a succeeding lift of the pressure cam and corresponding drop of the suction cam while the cylinders are in communication with the pressure channel, a succeeding dwell at the end of the piston stroke, a succeeding drop of the pressure cam and corresponding lift of the

suction cam beyond said normal level, and a succeeding lift of the pressure cam and corresponding drop of the suction cam to the normal level while the cylinders are in communication with the suction channel.

ROBERT DE STOUTZ.
